TERMINAL WIRING TOOL

Melvin T. Collier, 1346 11th St., Denver, Colo.

Filed Jan. 17, 1963, Ser. No. 73,215

Term of patent 14 years

(Cl. D54—13)

FIG. 1.

FIG. 2.

FIG. 3.

FIG. 4.

FIG. 5.

FIGURE 1 is a side elevation of the terminal wiring tool, showing my new design;

FIGURE 2 is a top plan view;

FIGURE 3 is a bottom plan view showing the tool in extended operative position;

FIGURE 4 is a front end elevation; and,

FIGURE 5 is a rear end elevation.

I claim:

The ornamental design for a terminal wiring tool, as shown.
